UNITED STATES PATENT OFFICE.

JOHN W. BARWELL, OF WAUKEGAN, ILLINOIS.

PULVERIZER.

1,201,135.

Specification of Letters Patent.

Patented Oct. 10, 1916.

Application filed October 12, 1914. Serial No. 866,303.

To all whom it may concern:

Be it known that I, JOHN W. BARWELL, a citizen of the United States, residing at Waukegan, in the county of Lake and State 5 of Illinois, have invented certain new and useful Improvements in Pulverizers, of which the following is a specification.

This invention relates more particularly to a machine which is especially adapted for 10 grinding or pulverizing grain for manufacturing meal or flour, although it may also be used for pulverizing various other substances.

Among the objects of this invention are 15 to provide a pulverizer or grinding apparatus which will be comparatively simple and cheap in construction, and exceedingly effective in operation; to provide such a machine in which the wearing parts may be 20 readily changed when worn or injured; to provide a machine in which a sieve or screen may be readily inserted and removed, and ordinary screen material may be used without any special preparation or construction; 25 and, in general, to provide such an improved construction as will appear more fully from the following description, taken in connection with the accompanying drawings.

In these drawings: Figure 1 is a vertical 30 sectional view of the machine; Fig. 2 is a cross section taken on the line 2—2 of Fig. 1; Fig. 3 is a plan view of the lower portion of the casing, showing the screen in position; and Fig. 4 is a perspective view of the upper portion of the casing.

As shown in these drawings, 5 represents a frame or casing, comprising a substantially rectangular bottom portion 6, and a semi-cylindrical top or cover 7. For convenience 40 in construction, the bottom portion and top may be divided longitudinally in the manner indicated, and the sections fastened together by means of bolts 8 and 9. The bottom portion is provided around the upper flange 45 with pivoted eye-bolts 10, which engage with slots 11 in the flange 12 of the top or cover 7, which bolts serve as a means for readily securing the top in position. The frame or casing 5 is open at the bottom, and 50 rests upon a base 13, which has an opening 14 therethrough, forming an outlet or discharge aperture for the machine. A hopper 15 may be placed under the discharge for receiving the pulverized material.

Stands 16 are secured to the base 13, and

are provided with roller bearings 17 for a shaft 18. As this machine is of the centrifugal type, and is adapted to run at high speed, approximately three thousand revolutions per minute, such roller bearings form 60 a desirable method of supporting the shaft. A driving pulley 19 is mounted on the shaft 18, and is driven by a belt 20 from any suitable source of power. The shaft 18 passes centrally through the frame or casing 5, and 65 is provided with a hub 20 within the casing, which hub may be made integrally with the shaft, or may be secured thereto in any well-known manner. The hub 20 is provided with three peripheral grooves 21, 22 and 23. 70 The grooves 21 and 22 serve to receive the inner ends of the beater arms 24. These arms are arranged in pairs, and each pair is connected at the outer end with a blade or bar 25. These blades or bars extend approximately the full length of the interior 75 of the machine, only a sufficient clearance distance being left between the ends of the bars and the inner wall of the casing. The hub 20 is provided with longitudinal holes 80 26 adjacent to the outer periphery for the pivot pins 27, which pins engage with the inner ends of the arms 24. Two pins are preferably provided for each pair of arms, and these pins are held in position longitudinally by means of cotter pins 28, the 85 groove 23 permitting the insertion of these cotter pins in the inner ends of the pivot pins.

The inner surface of the top or cover 7 is furnished with any suitable form of abrading plates or devices, to co-act with the beaters. A simple form of such devices 90 consists of corrugated plates 29, which are made in sections, as shown particularly in Fig. 2, so that they may be readily inserted and may be readily removed for replacing. These plates are held in place by bolts 30, and their adjacent edges are formed so as 95 to overlap, which also tends to hold them more securely in position. Ordinarily there will be but slight clearance between the beaters 25 and the inwardly projecting portions of the plates 29, such clearance being about one-quarter of an inch in machines which I have constructed.

Semi-circular grooves 31 and 32 are made in the inner faces of the sides of the lower portion 6 of the casing, these grooves being 100 concentric with the axis of the shaft 18, 110

and the center of the semi-cylindrical top or cover. A screen 33, which may be made simply by cutting a piece of suitable material to the proper length and width, is slipped into the grooves 31 and 32, which hold it securely in position. This furnishes a simple method of holding the screen, and an arrangement whereby the screen may be easily removed and replaced when desired.

10. The top 7 has an opening in one side thereof, about midway between the center and the outer periphery, which serves as an inlet for the material to be pulverized. A chute or pipe 35 is secured to the side of 15 the casing for directing the material into the opening 34.

When the machine is at rest, the pivoted beaters will tend to swing by gravity to such positions as indicated by dotted lines 20 in Fig. 2. Then, as the shaft 18 is turned, these beaters will gradually swing out until they assume approximately radial positions. Any material which is directed through the 25 inlet 35 will be engaged by the beaters, both the flat portions of the arms and the horizontal blades tending to engage with the material and throw it out against the inner grinding surface of the top. The centrifugal force, due to the high velocity of the 30 rotating parts, will constantly tend to throw the material to the grinding surface, where it will be quickly and effectively pulverized. Such centrifugal force, together with the 35 action of the beaters, will also agitate the material and force it out through the screen or sieve 33 as fast as it becomes sufficiently pulverized or reduced to go through the screen. The pulverized material then passes down into the hopper 15, and may be taken 40 away as desired. Any suitable number of beaters may be arranged in the machine, but a relatively small number will do very effective work. Also, on account of the peculiar form of the beaters and the arrangement 45 of the beater blades, comparatively little room is occupied by the arms, and this provides a large capacity for the incoming material, so that more material will be constantly acted upon than if the central portion 50 of the machine were filled with a larger number of arms or fingers. The hinged or pivoted beaters also provide an arrangement whereby, if some foreign substance, such as a piece of iron or the like, passes 55 into the machine, it will not be apt to break the same, as the beaters will swing back in order to pass the obstruction. Such an obstruction will, however, ordinarily be noted by the unusual noise or racket, and the op-

erator may then stop the machine and remove the article.

I have found this machine exceedingly effective in actual operation, and it has proven to have a high pulverizing or grinding capacity. While I have shown a preferred form, it will be apparent that various changes may be made in details of construction without departing from the spirit of this invention, and therefore I do not wish to be limited to the exact construction shown, except as specified in the following claims, in which—

I claim:

1. In a pulverizer, the combination of a shaft having a hub thereon, and having two grooves spaced at some distance from the ends thereof, pintles passing longitudinally through the outer portions of the hub, two twisted bars pivoted on each pintle, grinding plates of angular cross section secured 80 to the outer ends of said bars and arranged parallel to the shaft, and means for fastening said plates to the bars, the arrangement being such that the plates may be reversed to present different edges for grinding. 85

2. In a pulverizer, the combination of a casing, a shaft passing centrally through said casing, a hub on said shaft extending substantially the full length of the casing and having two grooves spaced at some distance from the ends thereof, and a central groove, pintles passing longitudinally through the outer portions of the hub and having cotter pins arranged within the central groove to hold them in position, pairs 90 of arms pivotally mounted on said pintles, with their ends fitting in said end grooves, whereby the arms are spaced at some distance from the ends of the casing, and cross bars secured to the outer ends of said arms, 100 and extending substantially the full length of the casing, the arrangement being such that the pivot pins and cotter pins are protected by the hub, and also such that a substantial space is left between the arms and 105 the ends of the casing.

3. In a pulverizer, a casing with a rotary beater therein, having a shaft with a plurality of radial grooves therein, arms pivoted in two of said grooves and having 110 pivots projecting into an intermediate groove, said arms having crushing means secured to their outer ends.

JOHN W. BARWELL.
